(57) **CLAIM**

The ornamental design for a chair, as shown and described.

DESCRIPTION

FIG. 1 is a front perspective view of a chair according to the present invention;

FIG. 2 is a rear perspective view of the chair of FIG. 1.

FIG. 3 is a side elevational view of the chair of FIG. 1, the other side being a mirror image thereof;

FIG. 4 is a front perspective view of a second embodiment of the chair of FIG. 1 without the arm rests;

FIG. 5 is a rear perspective view of the chair of FIG. 4;

FIG. 6 is a side elevational view of the chair of FIG. 4, the other side being a mirror image thereof;

FIG. 7 is a front perspective view of a third embodiment of a chair according to the present invention;

FIG. 8 is a rear perspective view of the chair FIG. 7;

FIG. 9 is a side elevational view of the chair of FIG. 7, the other side being a mirror image thereof;

FIG. 10 is a front perspective view of a fourth embodiment of the chair of FIG. 7, without the armrests;

FIG. 11 is a rear perspective view of the chair of FIG. 10; and,

FIG. 12 is a side elevational view of the chair of FIG. 10, the other side being a mirror image thereof.

The fragmented cross-hatching shown on the seat and backrest members is understood to represent fabric and would be continuous throughout the circumscribed areas.
